UNITED STATES PATENT OFFICE

LEONARD T. EVANS, OF INDIANAPOLIS, INDIANA

CONVEYER-SEPARATOR

Application filed February 11, 1929. Serial No. 339,143.

My invention relates to improvements in beater-conveyors. It is particularly designed for tumbling material for the purpose of shaking the same out, freeing the same from foreign matter and at the same time progressively moving the material forward. More specifically, the invention is designed for handling waste such as is used in packing journal boxes of railway cars and the like. In certain steps in the process of reclamation of this waste, it is desirable to fluff and shake the material so that all short fibers may be shaken out and all foreign matter such as cinders, Babbitt metal and the like may be shaken out so as to leave the waste free of foreign matter and free of short fibers. My invention is particularly designed for accomplishing this result and at the same time progressively moving the material forward so that it may, during its cleaning operation, be transported from one point to another.

In the embodiment of the invention illustrated,

Fig. 1 is a longitudinal section of a conveyor-beater embodying my invention;

Fig. 2 is a sectional view on the line 2—2 of

Fig. 1;

Fig. 3 is a sectional view on the line 3—3 of Fig. 1;

Fig. 4 is a detailed view showing more particularly the mounting of the conveyer slats;

Fig. 5 is a perspective view of one of the removable side walls of the casing and

Fig. 6 is a sectional view showing the mounting of said side walls.

In the structure illustrated, I provide a preferable semi-cylindrical casing or cover 1 supported on a suitable frame 2. The bottom edges of the casing are preferably supported on angle members 3 forming a part of the frame and extending downwardly and inclined slightly inwardly are deflector plates 4 which in effect form a continuation of a casing. These plates are removably mounted on the underside of the angle members 3, being provided with slots 5 in a lip or flange 6. These slots receive headed bolts 7 secured to the angle members 3 and are removably supported in position thereby.

A rotatable shaft 9 extends axially through

the casing being mounted in bearings 10 on the end members of the frame. This shaft has keyed thereon, to rotate therewith, a sleeve 11, on which is mounted a plurality of radially extending posts or arms 12^a to 12^c which at their outer ends support a foraminous cylinder 13. The longitudinal extent of this cylinder is not quite as great as the casing so that there is an overhanging projection 14 of the casing beyond one end of the cylinder.

The posts support a plurality of substantially helically disposed propellers. Each of these propellers comprises a plurality of slats 15 supported on the sides of the posts 12. The posts are so disposed around the tubular member 11, as to give the correct pitch to the propellers and while in general, the propeller member may be said to be helically disposed, their arrangement is somewhat peculiar. Starting at the front end, each propeller from the post 12^a to the post 12^b is given a decided dip or is concaved as at 16 and then spirals. From the post 12^b to the post 12^c the propeller sweeps on a spiral and from the post 12^c to the post 12^a, the propeller is given a slightly reverse curve so that from the post 12^a to the post 12^b, the propeller is substantially straight. This peculiar formation is provided in order that the greatest beating and fluffing effect can be obtained. When the material is first dropped into the receiving end of the device, it is desired that it shall be beaten and tumbled for a comparatively long period before it feeds forward. This tumbling is to loosen up the waste and open up the fibers. As a result the propeller at its receiving end is given such a formation that the progressive movement imparted to the waste is slight. After it has received its initial tumbling, the waste can then be moved forward more rapidly and at the central section of the propeller, the post is given such form as to, while continuing the tumbling operation move the material forwardly a little more rapidly. Due to this beating and forward movement the heavier particles of foreign matter, such for instance as Babbitt metal, cinders and the like which might occur in waste, are caused to drop out.

Furthermore, the greater portion of the short fibers are shaken out. As the waste reaches the delivery end, the feed is again slightly slowed up due to the more or less flattened portion of the propeller and the waste is given a greater tumbling action to thoroughly shake out all the short ends before it is delivered at the delivery end. To further assist in the fluffing of the waste during its tumbling action while being propelled through the cylinder 13 by the propeller, the propeller slats are provided on their rear faces, with picker fingers 17, upon which the waste drops during its tumbling movement and over which the waste is dragged in its movement.

At the receiving end of the cylinder 13 there is provided an arc shaped trough 18 opened at its top and arranged beneath the receiving end of the propeller to prevent the dropping of the waste out of the propeller prior to its entry into the cylinder 13.

The foreign matter, lint, etc., as the waste is propelled through the cylinder 13, drops through the openings in the cylinder and through the bottom opening 19 to the floor. The side deflectors 4 deflect this material so that it will fall in a heap toward the center of the machine and in order to obtain ready access to the cylinder. These sides 4, as above described, are made removable.

In some instances, it may be desired to deliver a current or blast of air to the waste as it is being tumbled and to this end, I provide air pipes 20 connected with a suitable source of compressed air by the pipe 21. These air pipes deliver air into the top of the casing 1 so that, the blast of air will assist in fluffing the waste and also assist in drying the same in event the waste is damp or wet.

The cylinder 13 is rotated by means of a suitable chain drive 22 from an electric motor or other source of power 23 and between the chain drive 22 and the shaft 9 of the cylinder 13, there is provided a friction clutch 24 which, in event the material becomes jammed will allow the motor to rotate without rotating the shaft 9.

I claim as my invention the following:

1. In a device of the character described, the combination with a rotating foraminous cylinder, of a rotatable propeller mounted within said cylinder to rotate therewith and comprising a plurality of helically disposed slats arranged side by side.

2. In a device of the character described, the combination with a rotatable foraminous cylinder, of a propeller rotatably mounted and extending through said cylinder comprising a plurality of helically disposed slats arranged side by side, the slats of said propeller being provided with picker fingers.

3. In a device of the character described, the combination with a rotatable foraminous cylinder, of a propeller mounted therein ro-

tatable therewith and comprising a plurality of blades, each blade comprising a plurality of helically disposed slats arranged side by side and extending through the cylinder.

4. In a device of the character described, the combination with a foraminous cylinder of a rotatable propeller mounted therein having a plurality of blades, each blade comprising a substantially helically disposed slatted member, the ends of each blade projecting beyond each end of said cylinder.

5. In a device of the character described, the combination with a foraminous cylinder, of a rotatable propeller mounted therein having a plurality of blades, each blade of which comprises a plurality of helically disposed slats arranged side by side, the pitch of said helices at the receiving end being greater than the intermediate portion and the pitch at the delivery end being less than the receiving portion.

6. In a device of the character described, the combination with a rotatable foraminous cylinder of a propeller mounted within and rotatable with said cylinder, comprising a plurality of blades each of which comprises a plurality of helically disposed slats arranged side by side, and a cover inclosing the upper portion of said cylinder.

7. In a waste tumbler, the combination with an enclosing cylinder casing having an opening extending substantially from end to end on its under side of a foraminous cylinder rotatably mounted in said casing, and a propeller member mounted within said rotatable cylinder and rotating therewith and comprising a plurality of blades, each of which comprises a plurality of helically disposed slats arranged side by side.

8. In a device of the character described, the combination with a rotatable foraminous cylinder, of a plurality of substantially helically disposed foraminous propellers arranged within said cylinder and rotatable therewith.

In witness whereof, I, LEONARD T. EVANS, have hereunto set my hand at Indianapolis, Indiana, this 18th day of January, A. D. one thousand nine hundred and twenty-nine.

LEONARD T. EVANS.
